J. F. PICKENS,

INVENTOR

Victor J. Evans

ATTORNEY

UNITED STATES PATENT OFFICE

JAMES FENTON PICKENS, OF BROWNSVILLE, PENNSYLVANIA

ILLUMINATED OIL CAN

Application filed June 20, 1930. Serial No. 462,677.

This invention relates to an illuminated oil can, the general object of the invention being to provide a lamp on the can which is so situated as to illuminate the contents 5 of the can and also the spout, thus enabling the can to be readily used at night or in dark places without danger of spilling the oil.

This invention also consists in certain 10 other features of construction and in the combination and arrangement of the several parts, to be hereinafter fully described, illustrated in the accompanying drawing and specifically pointed out in the appended 15 claims.

In describing the invention in detail, reference will be had to the accompanying drawing wherein like characters denote like or corresponding parts throughout the several 20 views, and in which:—

Figure 1 is an elevation of the invention. Figure 2 is a top plan view.

Figure 3 is a section on line 3—3 of Figure 2.

25 Figure 4 is a section on line 4—4 of Figure 2.

As shown in these views, the can A is provided with a flange 1 at its top which is of inverted trough shape and at the front, 30 the top of the can is formed with an opening 2 which is located under the front part of the flange. A socket 3 is connected to the under face of the front part of the flange, at the center thereof, this socket being arranged adjacent the opening 2 so that some 35 of the rays of light from a lamp 4 placed in the socket will pass through the opening 2 and thus illuminate the interior of the can.

A conductor 5 is connected with a contact 40 6 placed in the socket and insulated therefrom and arranged to engage the central contact of the lamp. This conductor passes around a part of the flange and under the same and then the conductor passes down- 45 wardly into a tubular part 7 which forms the handle of the can and which is connected with the can by the bracket 8. Small batteries 9 are placed in the tubular part 7 and the conductor is connected to a sliding 50 switch 10 which has a part 11 for contacting

a terminal of one of the batteries when the switch is in lowered position. This switch passes through a slot 12 in the upper part of the tubular member 7 so that it can be moved upwardly or downwardly to make and break 55 the circuit of the lamp. When in its lowermost position, the switch will close the circuit to the lamp and when in raised position, the circuit will be broken.

From the foregoing it will be seen that the 60 lamp will not only illuminate the interior of the can, but it will also illuminate the spout B thereof and the part into which the spout is placed so that the user can readily place oil in a part at night or in dark places 65 without danger of spilling the oil and he can also see the contents of the can.

It is thought from the foregoing description that the advantages and novel features 70 of the invention will be readily apparent.

It is to be understood that changes may be made in the construction and in the combination and arrangement of the several parts, provided that such changes fall within the scope of the appended claims.

What I claim is:—

1. An oil can having an opening in its front, a lamp carried by a part of the can and arranged adjacent the opening whereby the lamp will illuminate the interior of 80 the can, said lamp also illuminating the spout of the can and means for supplying current to the lamp.

2. An oil can having an opening in its front, a lamp carried by a part of the can 85 and arranged adjacent the opening whereby the lamp will illuminate the interior of the can, said lamp also illuminating the spout of the can, means for supplying current to the lamp, such means comprising a 90 tubular handle part containing batteries, a conductor for connecting the batteries with the lamp and a switch for controlling the flow of current through the conductors.

3. An oil can having a flange at its top 95 which is of inverted trough shape in cross section and an opening in the top of its front wall, a lamp socket depending from the flange adjacent the opening, a lamp in the socket for illuminating the interior of 100

the can and the spout thereof, a tubular part forming a part of the handle of the can, batteries in the said tubular part, a conductor for connecting the batteries to the lamp and a switch in the tubular part for controlling the flow of current to the conductor.

5 In testimony whereof I affix my signature.

10 JAMES FENTON PICKENS.
